UNITED STATES PATENT OFFICE.

GEORGE J. DEHN, OF CHICAGO, ILLINOIS.

DRAIN-TRAP.

1,174,234.

Specification of Letters Patent.

Patented Mar. 7, 1916.

Application filed February 19, 1909. Serial No. 478,959.

To all whom it may concern:

Be it known that I, GEORGE J. DEHN, a resident of Chicago, in the county of Cook and State of Illinois, have invented certain new and useful Improvements in Drain-Traps, of which the following is a full, clear, and exact description.

The invention relates to drain-traps and designs to provide an improved drain-trap in which provision is made for preventing back-flow of the water through the outlet pipe and through the drain.

In back-water traps and drains it is customary to employ a check-valve which prevents back flow of the water from the outlet pipe. In practice it occurs that lint and other material frequently passes into the trap and becomes lodged on the valve seat or on the valve and thus renders the back-water valve inoperative.

One object of the invention is to provide an improved drain which is provided with a removable sediment-holding receptacle whereby matter, such as lint, which is likely to become lodged on the valve-seat or valve or to clog the passage in the trap pipe will be trapped or held so that the back-water valve will not be rendered inoperative to prevent back-flow of water or gas through the check-valve. By providing a removable sediment-holding receptacle in the basin of the drain to which the trap-pipe is connected in which matter, such as lint or other material likely to prevent the closing of the valve will be deposited and caught to prevent it from passing to the valve, the accumulation may be occasionally removed when necessary.

The invention further designs to provide an improved drain-trap which may be employed either as a floor-drain or connected to receive drain in drain outlets such as lavatories, or rinsing-basins or the like.

The invention still further designs to improve the construction of drain-traps so that they will contain a large body of water, which will not evaporate if not frequently used.

With these objects in view, the invention consists in the several novel features hereinafter set forth and more particularly defined by claims at the conclusion hereof.

In the drawings: Figure 1 is a side elevation of a drain-trap embodying the invention. Fig. 2 is a vertical longitudinal section. Fig. 3 is a section taken on line 3—3

of Fig. 2. Fig. 4 is a perspective of the receptacle for collecting sediment passing to the drain. Fig. 5 is a section taken on line 5—5 of Fig. 2. Fig. 6 is a section showing the drain in use as a floor-drain.

The improved drain comprises a basin 10 formed with a cylindrical body 11, and a bottom 13. This basin is adapted to receive the drain and to contain a body of water 65 sufficient to constitute an effective water-seal to prevent back-flow of gases from the sewer-pipe. A trap-pipe 14, integrally formed with the basin, communicates with the lower portion of the basin as at 15, and 70 extends upwardly to a horizontally extending outlet pipe 16 which is also integrally formed with the basin and trap-pipe 14. At the confluence of the trap pipe 14 and the outlet, a diagonally disposed check-valve 17 75 is provided. A suitable shoulder 18 integral with the trap-pipe and basin is adapted to receive a suitable valve-seat ring 19 which is secured on the shoulder by screws 20. The valve 17 is pivoted at its upper end to 80 the seat-ring 19 so that the drain from the trap-pipe will lift it to permit the drain to pass to the outlet pipe, but any back pressure of gas or water in the outlet pipe will seek the valve and prevent passage thereof 85 to the basin.

In manufacture, the seat-ring 19 is usually formed of brass to provide a non-corrosive seat, and an accurate fit between the valve and the seat. To permit the valve 90 and ring to be inserted in the outlet pipe, the inner portion of the latter is enlarged as at 22 and formed with an opening 23 through which the connected valve and ring may be inserted or removed. Said opening 95 is normally closed by a cap-plate 23. The outer end of the outlet pipe 16 is adapted for connection to a sewer-pipe or pipe leading to the sewer. The outlet pipe 16 has usually connected thereto a vent-pipe 24 100 as shown. As a result of the construction thus far defined, a large body of liquid will be contained in the basin and the pipe 14 below the check-valve to form an effective water-seal for preventing gases from the 105 sewer from flowing backwardly through the basin.

In practice, when the drain is infrequently flushed, the liquid forming the seal evaporates. In the present construction, 110 however, the entire lower portion of the basin and the trap-pipe contain so large a

body of water as to render unlikely sufficient evaporation to permit gases to flow backwardly through the basin. By providing a deep cylindrical body for the basin 5 and integral trap-passage or pipe 14 at one side thereof, it becomes possible to have a large body of liquid for the seal which will not entirely evaporate for a very long period, and furthermore, it may be installed 10 in the floor without necessarily employing a larger inlet for the basin than is ordinarily used.

In drain-traps as generally constructed, the trap-pipe is connected by a curved or 15 smooth passage to the liquid-chamber in the basin to facilitate the passage of all material reaching the basin into and through the trap-pipe. In lieu of this construction, however, the present invention utilizes a cylindrical basin much greater in area than the trap-pipe and a vertically or upwardly extending passage at the side of the basin. The use of this basin and trap-pipe is made 20 possibly by preventing the passage of lint or other material likely to accumulate in the trap-pipe, or in the back-water valve passing into said pipe or basin. A sediment-collecting receptacle 25 is disposed in the basin and removably held therein. This receptacle comprises a cylindrical body 26, a closed bottom 27, and an outwardly flaring mouth or flange 28 at its top, the upper portion of the body having formed therein ports or passages 29 for permitting the drain to 30 pass from the receptacle to the basin. The outer edge of flange 28 rests on a seat 30 formed in the wall of the basin and the flange directs the drain into the receptacle. The diameter of the body of the receptacle 40 is smaller than the body of the basin to leave a chamber between the receptacle and the basin for the passage of the drain from the receptacle to the bottom of the basin, so that the drain will flow out of the basin through 45 the pipe 14. A baffle 31 overlies the chamber in the receptacle 25 and is provided with legs 32 resting on the upper portion of the receptacle to hold the baffle in separated relation from the flange 28. This baffle directs the drain onto the flared mouth or 50 flange 28 of the receptacle so that it will pass into the receptacle around the sides thereof and prevent it from flushing out the sediment deposited in the receptacle. The 55 receptacle 25 is thus removably held in the basin and may be withdrawn through the top of the basin whenever sufficient sediment has accumulated to render cleansing desirable or necessary. A rod 33 serves as a 60 handle whereby the receptacle may be lifted out of the basin. Arms or lugs 34 extend outwardly and downwardly from the bottom of the receptacle 25 to catch any material which may escape into the basin so that 65 it will not pass into the trap-pipe 14 or clog

the opening 15. The outer ends of the arms are connected by an annulus 35 and the latter and said arms are formed integral with the receptacle so that when the latter is lifted out of the basin the solid matter arrested 70 by the arms and ring will be withdrawn from the basin.

The operation of the trap thus far defined will be as follows: Drainage usually carrying solids in suspension passing into the 75 upper end of the basin will be directed initially into the receptacle by the inclined flange 28. The solids and matter likely to obstruct the trap-pipe or become lodged on the back-water valve will settle in the receptacle 80 25 and be collected thereby, while the liquid will pass through passages 29 to the chamber between the receptacle and the cylindrical wall of the basin. From the bottom of the basin the liquid will pass upwardly 85 through the trap-pipe 14, back-water valve 17 to the outlet pipe 16, a large body of liquid remaining in the basin receptacle and trap-pipe to form a liquid seal for preventing the return of gas from the sewer as 90 shown in Fig. 2. The back-water valve 17 being normally seated, will prevent water from being forced backwardly through the outlet pipe to the trap-pipe or basin. Resultantly, slimy matter, lint, etc., and all 95 solids likely to obstruct the liquid passages in the basin and trap-pipe, will be retained in the receptacle. The arms or lugs 34 further obstruct the passage of such matter to the trap-pipe 14 in event they should pass 100 through the passages 29 in the receptacle. At different times the sediment-receptacle 25 may be lifted out of the basin and cleansed so that the accumulation in the receptacle will not be sufficient to obstruct the 105 passages for the liquid. The basin is provided with an annular seat 36 adapted to hold a drain-plate 37 as shown in Fig. 6 when the trap is employed as a floor-drain. The top of the basin and plate 23 being substantially flush with the floor so that the plates 23 and 37 may be removed without disturbing the connections for the trap or floor in which it is laid when access to the 110 outlet pipe or valve 17 is desired.

In many instances it is desired to use the drain-trap for carrying off drain from pipes connected to lavatories or tanks or other receptacles. To adapt the drain-trap to receive drainage from such pipes, a bonnet 39 115 is secured to the top of the basin by screws 40 passing through an inturned flange 41 on the bottom of the bonnet. The top of the bonnet is closed by a cap-plate 41' which is removably held on the bonnet by 120 clamp-screws 42 which are pivoted as at 43 to lugs on the outer side of the bonnet and are provided with nuts 44 for clamping the cap on the top of the bonnet to provide 125 an air-tight closure for the bonnet. A 130

gasket 45 is usually interposed between said plate and the bonnet. Thus, whenever it may be desired to withdraw the sediment holding receptacle 25 from the basin, the 5 cap-plate 41 may be removed to permit it to be lifted out of the basin and out of the bonnet without disturbing the drain-pipes connected to the bonnet. Openings 46 and 10 47 are provided at opposite sides of the bonnet so that a vent-pipe 48 may be connected to either side of the bonnet according to the location of the bonnet with respect to the vent-pipe while the opening which is not in use for a vent-pipe may be 15 closed by a plug 48'. If desired both openings 46 and 47 may be used at the same time to cause a more effective ventilation or circulation of air over the inlet side of the liquid seal. The bonnet is also provided 20 with means for connecting a drain-pipe to both or either of the sides thereof, such as a screw-threaded opening 50 adapted to receive a drain-pipe 51 or a short pipe 52 adapted to receive the flanged terminal of 25 a drain-pipe, such construction being well understood in the art. Each opening in the bonnet for a drain-pipe is normally closed by a check-valve 53 adapted to permit liquid to pass into the bonnet through the drain- 30 pipes and prevent back-flow through said pipe. Each of said valves is preferably inclined so that it will be held against its seat by gravity and is pivoted as at 54 to a seat-ring 55 secured against the inner 35 face of the wall of the bonnet. The seats are secured to the wall of the bonnet by screws 56. Resultantly, back-flow of water or gas through either of the drain-pipes is avoided. Furthermore, when the bonnet is 40 connected to a plurality of drain-pipes, the drain will be discharged into the bonnet without permitting any thereof to pass into the other pipe which is closed against back-flow by a check-valve 53.

45 Thus the invention provides a drain-pipe in which provision is made for preventing the trap or back-water valves from becoming clogged or inoperative by slime or lint, etc., and which in lieu of passing through 50 the trap-pipe is collected in the removable receptacle in the basin and this receptacle can be removed and periodically cleansed. Furthermore, the improved drain-trap is adapted to be employed either as a floor 55 drain or to receive drainage from drain-pipes leading to lavatories or sinks or other receptacles. When used either as a floor-drain or a drain-trap for drainage dis-

charged into the trap from pipes, the sediment-holding receptacle may be readily and 60 quickly withdrawn for cleansing whenever necessary.

The invention provides a drain-trap in which provision is made for the circulation of air in the receiving-basin and this constitutes an important feature of the invention, particularly when applied to a drain for a garage. Many explosions have occurred from the ignition of gases forming 65 in the drain-trap where gasolene is used, which causes the formation of combustible vapor in the trap. By providing ventilation at the inlet side of the liquid-seal, the gasolene, which passes to the drain and is of less specific gravity than water, and 70 floats on top of the seal, will evaporate and be carried off through the vent-pipe or pipes and therefore, prevent explosions.

The invention is not to be understood as restricted to the details of construction set 80 forth since these may be modified within the scope of the appended claims without departing from the spirit and scope of the invention.

Having thus described the invention, what 85 I claim as new and desire to secure by Letters Patent, is:

1. In a drain-trap, the combination of a basin having an opening in its top, a sediment-collecting receptacle having a surrounding wall and openings in said wall, a chamber being formed between said wall and the basin-wall for the passage of liquid from the receptacle to the basin, outwardly extending lugs on said receptacle for arresting 90 solid matter and removable with the receptacle, said lugs being disposed above the bottom of the basin, and a trap-pipe leading from the basin.

2. In a drain-trap, the combination of a basin having an opening in its top, a perforated sediment-collecting receptacle having an inclined flange at its top for directing the drain into said receptacle and fitting in the top opening of the basin, outwardly 105 extending lugs on the receptacle near the bottom thereof, a ring connecting the lower ends of said lugs, and a trap-pipe connected to said basin, a chamber being formed between the receptacle and the basin-wall for 110 the passage of drainage to the drain-pipe.

GEORGE J. DEHN.
